Primary Examiner — Lisa Lichtenstein*(74) Attorney, Agent, or Firm* — Jeffrey A. Ruppel(57) **CLAIM**

The ornamental design for an engine exhaust treatment device housing, as shown and described.

DESCRIPTION

FIG. 1 is a perspective view of an engine exhaust treatment device housing of our design;

FIG. 2 is a right side view thereof;

FIG. 3 is a top view thereof;

FIG. 4 is a front view thereof;

FIG. 5 is a left side view thereof;

FIG. 6 is a bottom view thereof; and,

FIG. 7 is a rear view thereof.

The broken line showing of a portion of an engine exhaust treatment device housing is included for the purpose of illustrating environmental structure and forms no part of the claimed design.
